(57) **CLAIM**

The ornamental design for a sign, as shown and described.

DESCRIPTION

FIG. 1 is a perspective view of a sign, incorporating the new design;

FIG. 2 is a front elevation view of the sign of FIG. 1;
FIG. 3 is a side elevation view of the sign of FIG. 1; and,
FIG. 4 is a top view of the sign of FIG. 1.

The underside of the sign is plain and unornamented. The
broken lines are shown for illustrative purposes only and
form no part of the claimed design.
